UNITED STATES PATENT OFFICE

DAVID W. RAYMONDS AND PAUL J. SCHWARZHAUPT, OF SCOTIA, NEW YORK, ASSIGNEES
TO GENERAL ELECTRIC COMPANY, A CORPORATION OF NEW YORK

SOUND RECORDING APPARATUS

Application filed March 20, 1930. Serial No. 437,521.

Our invention relates to phonograph sound recording apparatus and particularly to such apparatus which is adapted to be used by the public and by which a person may record a spoken message which may be transmitted, for example by mail, in lieu of a written letter. It is the object of our invention to provide an improved apparatus of the above mentioned character which shall be reliable, efficient, convenient and simple to operate, protected against theft of parts and misuse of the apparatus, and inexpensive to manufacture.

Our invention will be better understood from the following description taken in connection with the accompanying drawings and its scope will be pointed out in the appended claims.

Referring to the drawings, Fig. 1 is a perspective view of the recording mechanism involving our invention; Fig. 2 is a side view of the cabinet containing the recording mechanism with parts broken away; Fig. 3 is a perspective view of the booth which contains the recording apparatus; and Fig. 4 is a circuit diagram of the apparatus.

In Fig. 3 we have shown our recording apparatus enclosed in the booth 1 which is constructed with sound proof walls and door. The door 2 is spring-closed and normally is locked in closed position. To gain entrance to the booth the door is first unlocked electrically by means to be described later and then is pulled open by the handle 3 thereon. To open the door from the inside it is provided with the handle 4, the turning of which operates the latch 5. Within the booth is the recording cabinet 6, the microphone 7, the driving motor 30 into which the operator speaks and which is adjustably suspended from the ceiling, the hand switch 8 for controlling the starting and stopping of the recording mechanism, the signal lights 9 and 10, the dome light 11, and the record blank vending machine 12. In this vending machine are a number of record blanks adapted for use with the recording apparatus, the machine being constructed to release one record blank each time that the proper coin is inserted in the slot 13 and the handle 14 operated. Vending machines

of this character are well known and therefore do not need a detailed description. The coin controlled apparatus for releasing a record blank also controls the unlocking of the booth door. For this purpose the shaft 55 of the handle 14 has mounted thereon the cam 16, see Fig. 4, which upon being rotated to the right engages contact spring 17 which in turn engages and moves contact spring 18 against the fixed contact 19. When the door 60 is closed the latch 5 cannot be moved from the exterior of the booth and the door can be unlocked only by a withdrawal of the catch 21. This member is pivotally mounted at 22 and is spring-pressed in the locking position. 65 To move the catch to the unlocking position there is provided an electromagnet comprising the winding 23 and the core 24. By closing of the circuit between springs 17 and 18 the magnet is energized and the catch is 70 withdrawn from the latch 5. In so doing, contact springs 25 are actuated to close a holding circuit shunted about spring 17 and 18 so as to hold the door unlocked after the handle 14 has been released. The door may 75 now be swung open and in so doing contacts 27 and 28 mounted on the door are separated. Since these contacts are in series with the winding 23, the catch thereby is released ready to hold the door when it swings shut. 80

Referring now to the mechanism by which the record is cut while the operator speaks into the microphone 7, the driving motor 30 connects through the worm gearing 31 to the shaft 32 having therein a vibration absorbing coupling 33. On the upper end of shaft 32 is mounted the turntable 34 upon which the record blank 35 is adapted to be supported. Mounted on suitable guide rods 36 and 37 is the carriage 38 which supports the cutting stylus and which is moved slowly and uniformly in one direction by the motor 30. For this purpose the carriage is provided with a half nut 40 mounted on a short shaft 41 having head 42 and having the spring 43 90 for normally pressing the nut into engagement with the screw 44. The latter forms a part of the horizontal shaft 45 which is connected by worm gearing 46 with shaft 32. Pivotaly mounted on the upper por- 100

tion of the carriage 38 is the lever 48 at one end of which is the electromagnetic stylus actuating member 49 and at the opposite end of which is the cam 50. The carriage at a predetermined point in its forward recording movement engages the rod 52 which by connection with the contact spring 53 opens the motor circuit between it and the contact spring 54.

- 10 The apparatus is constructed to have the carriage returned by the manual operation of the hand lever 56, it being necessary for the operator to return the carriage to its initial position in order to remove the record 15 from the turntable. From Figs. 2 and 3 it will be seen that the carriage and recording stylus are completely covered by the housing 57 which until the carriage is moved to its initial position does not permit of the 20 removal of the record blank. Before any return movement of the carriage is initiated the stylus must be lifted from the record and the half nut 40 must be withdrawn from the cooperating screw. To bring about these 25 results we have provided the apparatus now to be described. Shaft 60 mounted on the carriage has at its lower end the bell crank lever 61, one arm of which is forked and engages the shaft 41 beneath the head 42 and 30 the other arm carries a roller 62 adapted to be engaged by the lever 63 secured through shaft 64 to the hand lever 56. At the upper end of shaft 60 is the finger 66 which is shown 35 projecting through a slot in the carriage and arranged to engage the cam 50 on lever 48. When hand lever 56 is pulled up by the operator, lever 63 engages roller 62 which through the bell crank 61 and shaft 41 withdraws the half nut 40 from its shaft and 40 through finger 66 depresses the adjacent end of lever 48 so as to lift the stylus from the record blank. Continued movement of the hand lever 56 causes the entire carriage with parts connected therewith to slide on its 45 guides 36 and 37 to its initial position. Just before it reaches its final position it engages the spring 67, compressing it a small amount while a squared portion of the bell crank 61 engages one or the other of the two hooks 50 68 and 69 which retains the carriage in the returned position. The hand lever 56 may then be released and by spring 70 is returned to its initial position. The two hooks 68 and 69 are identical in construction, being both 55 pivoted on the stud 72 and being connected by similar links 73 and 74 through pin and slot connections with the rocking plate 75. This plate is connected through shaft 76, crank 77, rod 78 and eccentric 79 to shaft 32 60 so that when the turntable is again started the two hooks 68 and 69 will be caused to oscillate in opposite direction, thus whichever hook retained the carriage in its returned position will release the carriage and 65 permit spring 67 to move it forward until

the nut 40 begins to engage the screw 44. It will be noted that in Fig. 1 the two hooks are shown for convenience in their mid-position, that is, opposite each other, which position corresponds with the mid-position of the eccentric 79 rather than to an extreme position thereof as illustrated. Upon the return movement of the carriage the stylus was further lifted off the record blank by the engagement of the lever 48 on the cam 80 which is 75 fixed in position and is so constructed that the stylus operating mechanism 49 is lifted sufficiently high to enable the operator easily to remove the record without its touching the stylus.

Inasmuch as the record blanks which are furnished for use with this machine are adapted to receive a record on both sides and since it is desirable to make provision in the machine for permitting two operations of the machine but preventing more than two, we have shown the machine as having the mechanism now to be described for limiting the operation thereof to two recordings for the insertion of each coin in the coin-controlled mechanism. Without such a provision it would be possible for a person to take with him into the booth a number of record blanks which might be home-made or obtained through outside sources and beat the machine by making a large number of records at the cost of a single coin. At the lower end of the carriage 38 is mounted a spring-pressed pawl 82 which engages the ratchet 83 to which is secured the cam 84 and one end of the strap 85 to which is attached the spring 86. Cam 84 is adapted to engage the contact spring 87 and separate it from contact spring 88, it being understood that a suitable stop, not shown, is provided for the cam 84 when it is returned by the spring 86. Spring-pressed pawl 90 retains the ratchet and is adapted to be withdrawn from engagement therewith by the lever 91 operated by the electromagnet 92. The first return movement of the carriage after a record has been cut on one side of the blank rotates the ratchet wheel 83 one tooth causing cam 84 to approach but not touch the spring contact 87. The second return movement of the carriage after the other side of the record blank has received its record rotates the ratchet another tooth and brings the cam 84 into position to open the circuit between springs 87 and 88 which, as will be described later, renders the mechanism inoperative for any further recording until the coin-operated device has again been operated.

For the control of the two signal lights 9 and 10, which are shown arranged in front of the operator and which preferably are green and red respectively, we have provided the control switches 95 and 96. The former is closed in response to the downward movement of the stylus actuating mechanism 130

49, being adjusted to operate when the carriage in its forward movement reaches the point at which the lever 48 in riding down the cam 80 allows the stylus to come into contact with the record blank. Thus the lighting of the green signal lamp 9 notifies the operator that it is time to begin to talk. When the carriage in its forward movement approaches its limiting position, namely reaches a point at which the operator has but a few seconds more to talk before the turntable is automatically stopped, it rides on an inclined portion of the switch 96 and closes the circuit thereof thus illuminating the red signal lamp 10.

During the recording process the shavings from the blank fall from the turntable into the receptacle 97 which surrounds the turntable. Connected with this receptacle by the pipe 98 is the motor driven exhausting fan 99 and the collecting bag 100. The turntable preferably is provided with two wipers or brushes 101 which move the shavings toward the opening of the suction pipe 98 and pulverize the same. The motor of this fan is connected to the switch 102 mounted on the door and arranged to be operated by the unlocking movement of the handle 4 mounted on shaft 103.

The switch 102 normally engages the fixed contact 104 which is included in the operating and holding circuit of the master relay 105 having armature 106. When switch 102 is operated, however, it breaks contact 104, thus releasing the master relay, and engages a second fixed contact 107 which closes the circuit of the motor of the exhausting fan 99. The hand switch 8 by which the turntable is started and stopped at the will of the operator controls the motor relay 109 having armature 110 by which the motor circuit is controlled.

Mounted preferably beneath the apparatus cabinet 6 in the booth is the cabinet 112 containing suitable thermionic amplifying devices connected with the microphone 7 and with the electromagnetic cutter 49. Through the leads 113 circuit connections for the motors, the signal lights, the relays, the magnets, etc. are made with a suitable source of operating current.

The operation of the above described apparatus is as follows: An operator desirous of recording a message would, according to printed instructions, first insert a suitable coin, for example a 25¢ piece, in the slot 13 and then turn the handle 14. The turning of the handle 14 operates to release one record blank from the bottom of the vending machine 12 within the booth and by the closing of the circuit at contacts 17 and 18 by cam 16 energizes the coil 23 to unlock the door, which it will be understood was previously closed and locked. The operation of the unlocking means closes the circuit between contacts 25 which shunts contacts 17, 18 to hold the door

unlocked after the handle 14 has been released. The turning of the handle 14 also closes the circuit of the master relay 105 by the touching of contacts 18 and 19, this circuit being completed through the switch 102 and contact 104. As soon as the master relay 105 operates its armature closes a shunt circuit about contacts 18 and 19 by which the relay is locked in closed position. Closing of the relay 105 also closes the circuit of the dome light 11. The operator then pulls open the door and enters the booth, the opening movement of the door serving to release the door unlocking circuit by the separation of contacts 27 and 28 whereby upon assuming closed position the door again becomes locked. The operator now takes the record blank which was released from the vending machine and places it upon the turntable 34, it being noted that the carriage and the protective cover 57 has already been moved back clear of the turntable. The switch 8 is now grasped by the operator who stands or sits facing the microphone 7 ready to begin talking. The closing of the hand switch 8 energizes the motor relay 109 which in turn closes the circuit of the driving motor 30. As the turntable shaft 32 begins to rotate the eccentric 79 through its connections with the shaft 76 and rocking plate 75 causes the fingers 68 and 69 to oscillate whereby whichever finger was hooked over the bell crank 61 is caused to release the same and allow the carriage to be started on its forward movement by the spring 67. The half nut 40 thereupon engages the screw 44. As the carriage is slowly advanced the stylus supporting lever 48 slides on the cam 80 until the stylus is allowed to come into cutting engagement with the record blank. At this instant the switch 95 is closed which illuminates the green light 9 which is the signal to the operator that it is time to begin to talk. By releasing and closing the hand switch 8 the operator may stop and start the turntable as often as he pleases. When the carriage has progressed to a point which is within a few seconds of the limiting position, the carriage rides upon the inclined portion of switch 96 and in closing the circuit of that switch illuminates the red lamp 10, thus notifying the operator that he has but a few more seconds to talk. Upon reaching the limiting position the carriage engages the rod 52 which opens motor circuit at contacts 53 and 54. In this position of the carriage the record cannot be removed. The operator thereupon pulls up on the hand lever 56 which through lever 63, bell crank lever 61 and finger 66 first lifts the stylus from the record then withdraws the half nut 40 from the screw 44 and upon further movement pushes the entire carriage back until it again becomes engaged by one or the other or both of the two hooks 68, 69. In this return movement of the carriage the stylus sup-

porting lever 48 rides up on the cam 80 so as to provide ample clearance for the removal of the record blank from the turntable. The blank may now be removed from the turntable and taken away or if the operator prefers, he may continue his message on the reverse side of the blank. If he so desires he turns over the record, placing it on the turntable as before and again grasps the hand switch 8 and makes a second recording in the same manner as he did the first. The first time that the carriage was moved back by the hand lever to its initial position the ratchet 83 was rotated one tooth, namely to the position shown in Fig. 1. In this position cam 84 attached to the ratchet wheel approached but did not touch the contact spring 87. By the second turn movement of the carriage the ratchet wheel 83 is rotated another tooth which is sufficient to bring the cam 84 into operative engagement with the contact spring 87 so as to open at that point the control circuit of hand switch 8. The operator is powerless thereafter to start the motor until the ratchet and cam have been restored to their initial position. The ratchet is maintained in its rotated position by the spring pressed pawl 90 which pawl is adapted to be released by the energization of magnet 92.

The operator now removes the blank from the turntable and by turning the door handle 4 unlatches the door and steps out of the booth. The act of turning the handle 4 to unlock the door operates through the shaft 103 and switch 102 to break the holding circuit of the master relay 105, allowing this relay to fall open. Operation of switch 102 also closes at 107 the circuit of the electromagnet 92 and the motor of the exhaust fan 99 so that for the brief interval that the door handle 4 is operated the exhaust fan is in operation to withdraw the shavings from the receptacle 97. The energization of magnet 92 by 45 causing the pawl 90 to release the ratchet 83 allows spring 86 to reset the ratchet and return cam 84 carried thereby to its initial position. Thus it will be seen that whether the operator has recorded on one or both sides of 50 the record blank his act of unfastening the door sets the machine ready for the next operator. Since the circuit of the master relay 105 was opened by the first movement of the door handle 4 and switch 102 the entire mechanism now is inoperative until the master relay is again energized by the insertion of another coin in the coin-control device and the turning of handle 14. Upon leaving the 55 booth the door swings closed and locks whereupon the entire apparatus is again in condition for another complete operation in the manner above described.

What we claim as new and desire to secure by Letters Patent of the United States, is:

1. Sound recording apparatus comprising

a rotatable member adapted to support a record blank, means for rotating said member, a stylus supporting carriage, latching means for retaining the carriage in an inoperative position, and means responsive to a movement of said rotating means for releasing said latching means. 70

2. Sound recording apparatus comprising a rotatable member adapted to support a record blank, means for rotating said member, a stylus supporting carriage, a plurality of latching members for retaining the carriage in inoperative position, and means operatively connected with said rotating means for successively moving said latching members to unlatched position. 75

3. Sound recording apparatus comprising a rotatable turntable, a stylus supporting carriage, means for moving the carriage uniformly during the recording operation, means by which the carriage is moved to an inoperative position, a pair of latches for retaining the carriage in said inoperative position, and means operatively connected with said turntable for alternately lifting said latches to releasing position. 80

4. Sound recording apparatus comprising a turntable adapted to support a record blank, a stylus carrying carriage, a motor for rotating said turntable and advancing said carriage, means by which the carriage is returned to its initial position, a summation device arranged to be actuated by each return movement of the carriage, a switch for controlling the circuit of said motor, and means responsive to a second return movement of said carriage for rendering said switch inoperative to start the motor. 95

5. Sound recording apparatus comprising a turntable adapted to support a record blank, a stylus carrying carriage, a motor for rotating said turntable and advancing said carriage, means by which the carriage is returned to its initial position, a ratchet device arranged to be moved a tooth in response to each return movement of the carriage, means responsive to a predetermined movement of said ratchet device for rendering the motor inoperative to rotate the turntable, and manually controlled means for resetting said ratchet device. 100

6. In combination, a booth having a door, sound recording apparatus therein, means responsive to the opening of the door by an operator within the booth for rendering the recording apparatus inoperative, and coin controlled means for rendering the recording apparatus again operative. 110

7. In combination, a booth having a door, sound recording apparatus therein having means for rendering it inoperative after a predetermined number of operations, means responsive to the opening of the door by an operator within the booth for restoring said first means, a second means responsive to said 115

opening of the door for rendering the recording apparatus inoperative and coin-controlled means for restoring said second means.

5 8. In combination a booth having sound recording apparatus located therein and having a door provided with a lock biased to locking position, a vending machine including a coin-controlled member, means controlled

10 by said member for moving the lock to unlocking position to permit opening the door, and means responsive to an opening movement of the door for causing the release of said lock.

15 9. Sound recording apparatus comprising a rotatable support adapted to carry a record blank, a carriage, a stylus carrying member movably mounted thereon, means operatively connected with said support for

20 advancing said carriage, and means responsive to the advance of said carriage for controlling the movement of the stylus carrying member relative to the support and to the carriage at the beginning of the recording operation.

25 10. Sound recording apparatus comprising a rotatable support adapted to carry a record blank, a stylus carrying member mounted for movement across said support and for movement toward and from the same, a signal device, and means for operating said signal device in response to movement of said member toward said support.

30 11. Sound apparatus comprising a turntable adapted to support a record blank, a carriage, a stylus supporting member carried thereby, means for slowly advancing said carriage in the forward direction relative to the blank from an initial inoperative position, means for maintaining the stylus out of engagement with the blank during said forward movement until a predetermined point is reached, and means operative to lift the stylus from the record and return the carriage to

45 its initial position.

12. Sound recording apparatus comprising a turntable adapted to support a record blank, a stylus carrying member, a motor connected to rotate the turntable and to advance the member, manually operable means for starting and stopping said motor at the will of the operator, a signal device, a controlling switch therefor arranged to be operated when the member approaches the limit of its movement, and a switch arranged to be operated when the member reaches the limit of the movement for deenergizing the motor.

50 13. Sound recording apparatus comprising a rotatable support adapted to receive a record blank, a stylus carrying member adapted to be moved toward and across said blank, a plurality of signal devices, means for actuating one of said devices in response to a blank engaging movement of said member, and means for actuating the other of said

devices when said member approaches the limiting position of its movement across the blank.

14. Sound recording apparatus comprising a turntable adapted to support a record blank while a record is being cut therein, a receptacle arranged to receive the shavings falling from said blank, said turntable having means for pulverizing the shavings and a suction device connected to withdraw the shavings from said receptacle.

15. Sound recording apparatus comprising a turntable adapted to support a record blank while a record is being cut therein, a receptacle surrounding said blank for catching the shaving therefrom, said turntable having means thereon cooperating with the receptacle for pulverizing the shavings and a motor driven suction device connected with said receptacle for removing the pulverized shavings therefrom.

16. Sound recording apparatus comprising a turntable adapted to support a record blank during the cutting of a sound record, a receptacle arranged to surround said turntable and to catch the shavings therefrom, and a suction device connected with said receptacle, said turntable having wipers carried thereby adapted to pulverize said shavings and to move them toward the entrance to the suction device.

In witness whereof, we have hereunto set our hands this 17th day of March, 1930.

DAVID W. RAYNOLDS.
